FOLDING CHAIR

Carl H. Oermann, York, Pa.

Application March 19, 1936, Serial No. 69,616

1 Claim. (Cl. 155—75)

This invention relates to chairs, particularly to folding chairs of the type commonly used on steamers, beaches, lawns, porches, etc.

An object of the invention is to provide an improved chair of the above type which is easily folded into a very compact condition when not in use or for transportation.

Another object of the invention is to provide an improved folding chair of the above type which may be provided with rockers.

Another object of the invention is to provide an improved folding chair of the above type with which are incorporated means for enabling the chair to be either folded or unfolded with a minimum amount of effort.

Another object of the invention is to provide an improved chair of the character mentioned, which is simple in construction, and reliable and exact in function under all conditions of service.

The invention also comprises certain new and useful improvements in the construction, arrangement and combination of the several parts of which it is composed, as will be hereinafter more fully described and claimed.

In the accompanying drawings:—

Figure 1 is a perspective of a chair constructed according to my invention and having rockers attached to the legs;

Fig. 2 is a perspective of a chair similar to the chair shown in Fig. 1, constructed without rockers; and

Fig. 3 is a vertical longitudinal section of the chair shown in Fig. 1.

Referring to the drawings, the chair comprises front legs 11, positioned parallel to each other and connected by a rod 12 near the bottom, said rod being rigidly fixed in any suitable manner to brace the legs as is customary.

A pair of rear legs 14 are pivotally connected, as at 13, at their forward ends, to the front legs 11, at a point intermediate the front legs, said front legs extending a suitable distance above the point where the rear legs are connected thereto. When the chair is set up, the rear legs 14 extend rearwardly and downwardly at a suitable angle.

Spreading or relative movement of the rear legs 14 with respect to each other, is prevented by a tie rod 15, which is mounted in the outer end portions of the rear legs, as shown in Figs. 1 and 3.

Pivoted by pins 16 mounted in the upper end of the front legs 11, are the front ends of arm rests 17. The arm rests extend rearwardly, and the rear end of said arm rests are pivotally con-

nected by pins 18 to uprights 19 constituting the back frame pieces of the chair.

The uprights or back frame pieces 19 are connected, at spaced intervals below the pivot pins 18, by rods 20, 21 and 22.

The rod 20 is secured to the rear of the back frame pieces 19 and is shaped to fit or conform to the back of a person sitting in the chair, said rod 20 constituting a back brace.

The rods 21 and 22 may be in the form of rounds, rod 22 being rigidly secured to the back frame pieces 19 near the lower end thereof, and the rod 21 being tightly fixed to the back frame pieces 19 at a point intermediate the pivots 18 and the rod 22.

The lower ends of the uprights or back frame pieces 19 are connected to the rear legs 14 by links 23. One end of each link 23 is pivotally connected to upright 19 by a pin 24, and the opposite end of each link is pivotally connected to the rear leg 14 by a pin 25. The links 23 have a suitable length and the purpose of said links will be hereinafter more fully described.

The seat is formed of side rails 26 connected at their front ends by a rod 27. The rear ends of the side rails 26 are mounted on the rod 21, so that the seat frame is pivotally connected at one end to the back frame constituted by the uprights 19. Pivot pins 13 extend through the front end portions of the side rails 26 so that said side rails, as well as the rear legs 14, are pivotally connected to the front legs 11 at the same point.

As shown in Fig. 1, spanning the space between the uprights or back frame pieces 19, is a strip of suitable fabric 28, such as canvas, duck, or the like. The fabric 28 provides a back support for an occupant of the chair.

Two pieces of fabric 29 and 30, may be used for the seat, the piece of fabric 29 extending from rod 27 at the front of the seat to the rear rod 21, and the fabric 30 spanning the space between the side rails 26 and underlying the fabric 29, as shown in Fig. 3.

If so desired, the above described chair may be provided with rockers 31, as shown in Figs. 1 and 3.

Each rocker 31 comprises a curved piece of material, pivotally mounted on extensions of the lower tie rod 15 of the rear legs 14.

Near their front ends, the rockers 31 are connected by a tie rod 32, each end of which is fixed to the rockers.

The lower ends of the front legs 11 are formed with notches 33 for engagement with the tie

rod 32, and in order to connect the lower ends of the front legs 11 to the rockers 31 when the chair is set up, I utilize a pair of hooks 34. These hooks may be formed from a suitable length of stiff wire, one end of which is provided with an eye 35 for the reception of a pin 36 which is driven into the front leg 11, as shown in Fig. 3, so as to pivotally mount the hook on said leg.

The parts of the frame of the chair are so arranged and positioned relatively to each other as to permit the chair to be easily folded. The front legs 11 and the back frame pieces 19 are disposed in substantially the same plane. The rockers 31 are disposed outside of the plane of the front legs 11 and the back frame pieces 19, and the rear legs 14 inside thereof. The side rails 26 of the seat are disposed inside of the plane occupied by the rear legs 14.

When it is desired to fold the chair, the hooks 34 are first detached from the tie rod 32, thereby permitting the front legs to be moved upwardly and rearwardly to detach the notched portions 33 thereof from the tie rod 32. The frame of the chair is moved about the pivot provided by rod 15, and during such movement the rear legs 14 swing upwardly and the lower ends of the back frame pieces 19 move outwardly from the rear legs 14.

The outward swinging movement of the back frame pieces 19 is limited, due to the fact that the lower ends of said back frame pieces are connected to the rear legs 14 by the links 23. By so connecting the back frame pieces 19 and the rear legs 14 together, the distance the ends of said back frame pieces can move or swing outwardly will be limited, and, therefore this construction permits ready and easy shifting of the parts of the chair frame during the folding operation, whereby the back frame pieces 19 can be moved towards the rear legs 14 and the front legs 11 can also be swung inwardly towards the rear legs.

When completely folded, the several parts of the frame of the chair are nested together compactly, so that the chair can be easily carried or transported in a minimum amount of space.

Due to the provision of the links 23, when the chair is folded, the back frame pieces 19 will be retained in position with respect to the rear legs 14, since both ends will be joined together.

When it is desired to unfold and set-up the chair, the back is first pulled upwardly, and during such movement the back swings around the fulcrum provided by the pins 24 of the links 23.

Due to the pivotal connection of the arm rests 17 with the back provided by pivots 18, the piv-

otal connection of the seat side rails 26 with the back provided by rod 21, when the back is pulled upwardly and outwardly, as has been described, the front legs 11 will also be moved. The lower ends of the front legs 11 can next be moved over 5 and the notches 33 inserted on tie rod 32. During such movement of the front legs 11, the back frame pieces 19 can be manipulated so as to move the rod 22 so that said rod rests upon the rear legs 14. This action also moves the links 23 to 10 the position shown in Fig. 3, and the chair will be completely unfolded and ready for occupancy, after the hooks 34 are applied to the tie rod 32. The above operation can be readily accomplished by an inexperienced person, due to the fact that 15 the several parts of the chair frame are so connected together, as to permit easy movement thereof in the manner heretofore described.

When the rockers 31 are omitted, the cross rod 15 is so made as to terminate with the rear legs 20 14, and the notches 33 and hooks 34 are omitted from the front legs 11. Otherwise the plain or straight chair, is similar in construction to the chair having the rockers.

Changes may be made in the details of construction and in the arrangement of the parts above described within certain limits without departing from the spirit of the invention.

Having thus described my invention, what I claim is:—

In a chair of the type described, front legs connected near their lower ends by a transverse rod, rear legs pivotally connected to the front legs at an intermediate point below the upper ends of said front legs, a transverse bar connecting 35 the outer ends of said rear legs, back frame pieces connected by a pair of cross rods disposed, respectively, adjacent the lower end and the midpoint of said back frame pieces, arm rests pivotally connected at their front ends to the upper ends of 40 said front legs and at their rear ends to said back frame pieces at an intermediate point between the upper back frame cross rod and the upper end of said back frame pieces, a seat frame comprising side rails connected at their front 45 ends to the pivots connecting the rear legs and the front legs, the rear ends of said seat rails being pivotally mounted on the midpoint cross rod of the back frame, means connecting the lower ends of the back frame pieces with said 50 rear legs for permitting limited movement of the back frame with respect to said rear legs, a pair of rockers pivoted to the transverse bar at the outer end of said rear legs, and means for detachably connecting the lower ends of the 55 front legs with the front portion of said rockers.

CARL H. OERMANN.
